UNITED STATES PATENT OFFICE.

JOHN W. RAPP AND JOSEPH VANORIO, OF COLLEGE POINT, NEW YORK; SAID VANORIO
ASSIGNOR TO SAID RAPP.

AIRPLANE-RIB.

1,357,209.

Specification of Letters Patent. Patented Oct. 26, 1920.

Original application filed January 19, 1918, Serial No. 212,785. Divided and this application filed February 27, 1919. Serial No. 279,553.

To all whom it may concern:

Be it known that we, JOHN W. RAPP and JOSEPH VANORIO, citizens of the United States, and residents of College Point, 5 county of Queens, and State of New York, have invented certain new and useful Improvements in Airplane-Ribs, of which the following is a specification.

This invention relates to improvements in 10 airplane ribs and is a division of the subject matter included in our application Serial No. 212,785, filed on the 19th day of January, 1918.

In airplane ribs and particularly in metallic airplane ribs, it is desirable to procure the maximum resistance to strains of compression, tension and torsion with a minimum of weight, and in such metallic airplane ribs it is desirable because of the 20 homogeneity of the structure to produce such a rib made of a single piece of sheet metal.

By our invention, we are enabled in a rib formed from a single piece of sheet metal 25 to take advantage of the great resistance to bending and torsional strains afforded by top and bottom channel or hook-shaped longitudinals and a web which has struts in which the maximum amount of column 30 action of the metal thereof is procured. To these ends, we have produced an airplane rib formed from a single strip or blank of sheet metal cut to provide longitudinals comprising top and bottom longitudinally-folded portions of substantially channel or 35 hook-shaped cross section, and diagonally arranged struts of substantially triangular cross-section intermediate said top and bottom longitudinally-folded portions, the said 40 struts preferably being embossed to one side of a vertical plane passing through the axis through which strains of compression will pass when the rib is in use and having the free flanges of such struts bent to the opposite side of such a plane. Such a plane 45 will coincide with the vertical-disposed connecting portion between the struts and longitudinal and will pass through the opposite sides of the strut. A maximum of 50 column action of the metal of the strut will thus result.

Other objects of my invention will be in part obvious from the annexed drawings and in part indicated in connection there-

with by the following analysis of this invention.

This invention accordingly also consists in the features of construction, combinations of parts, and in the unique relationship of the members and in the relative proportioning and disposition thereof, all as more completely outlined in the following specification and in said drawings.

To enable others skilled in the art so fully to comprehend the underlying features of my invention that they may embody the same by numerous modifications in structure and relationship of parts contemplated by this invention, drawings depicting a preferred form have been annexed as a part of this disclosure, and in such drawings like characters of reference denote corresponding parts throughout all the views, of which:—

Figure 1 is a side elevation of a rib for aerofoil frames embodying my invention and connected at opposite ends to the tubular marginal frame;

Fig. 2 is an enlarged fragmentary view in side elevation of a portion of the rib shown in Fig. 1;

Fig. 3 is a section on the line 3—3 of Fig. 2;

Fig. 4 is a section on the line 4—4 of Fig. 2; and

Fig. 5 is a section similar to Fig. 4 of a modified form of rib, in which the embossing and bending are in the opposite direction from that shown in Fig. 4.

Referring now to these drawings, and particularly to Fig. 1, 1 indicates a rib which is formed from a blank of sheet metal indicated by dotted lines 2, which blank is suitably trimmed to aerocurve shape and is longitudinally bent or folded at its top and bottom marginal edges to produce longitudinals comprising channel or hook-shaped folded portions 3 and 3' respectively which will afford considerable resistance to bending and torsional strains. The web portion intermediate such longitudinally-folded portions is partially cut away to provide diagonally disposed struts 4 and interstrut openings 4' and a vertically-disposed connecting or rim portion 5. Each of the said diagonally disposed struts 4, in order to provide stiffness and rigidity, has the entire metal of such strut bent later-

ally into a form substantially triangular in cross-section. This bending of the metal greatly increases its column action over other constructions and thus increases the 5 resistance of the metal of the strut to strains of compression and when struts of this character are used in combination with the substantially tubular horizontally folded portions, a large measure of rigidity is 10 procured in the rib. We have been enabled to further increase the rigidity of the rib, however, and to procure the maximum amount of column action for the metal of such struts, by not only bending all the 15 metal into such triangular cross-section but by also bending such metal so as to extend on opposite sides of a vertical axis through which strains of compression will be applied when the rib is in use. To this end, therefore, we have embossed a part of the metal 20 of such strut portions and preferably the central portion to one side of a vertical plane passing through the said axis through which strains of compression will pass when 25 the rib is in use and have bent the free flanges of such struts so as to extend to the opposite side of such a plane. Such a plane will obviously coincide with the top and bottom vertically disposed connecting or 30 rim portions 5 and will cut through opposite sides of the triangular struts, and a maximum of column action of the metal of the strut will result. When struts so embossed and bent are used in combination 35 with the hook-shaped longitudinally folded portions, a rib is produced in which the strength, rigidity and factor of safety of the rib are materially increased.

It is apparent, therefore, that an aerofoil 40 frame when a series of ribs of this character are employed, parts 6 and 7 of which are shown, it will, owing first to the increase in column action procured by the bending of all the metal of the diagonally disposed 45 struts into a shape triangular in cross-section, second, to the further increase in column action due to the combined embossing and bending of the metal of the struts to opposite sides of the axis through which 50 strains of compression will be applied, third, to the resistance to bending afforded by the channel-shaped longitudinals, have, in proportion to its weight, greatly increased rigidity and strength over any rib 55 of equal weight and inherent tensile strength of metal, and will combine the advantages of homogeneity of structure with great strength.

Having described our invention, we claim:

1. A rib for aerofoils comprising, a single 60 strip of sheet metal embodying longitudinals comprising top and bottom longitudinally folded portions substantially channel-shaped in cross-section, formed by folding the upper and lower edges of a blank of metal 65 longitudinally and an intermediate web por-

tion having diagonally disposed struts and interstrut openings, the metal of each of the struts being bent laterally from edge to edge into a shape substantially triangular in cross-section. 70

2. A rib for aerofoils comprising a single strip of sheet metal, embodying longitudinals comprising top and bottom longitudinally folded portions substantially channel-shaped in cross-section, formed by folding the upper 75 and lower edges of a blank of metal longitudinally and an intermediate web portion having diagonally disposed struts and interstrut openings, the metal of each of the struts being bent laterally from edge to edge 80 into a shape substantially triangular in cross-section with a portion of such triangular web on opposite sides of a plane passing vertically through the axis through which strains of compression will be applied when 85 the said rib is in use.

3. A rib for aerofoils comprising a single strip of sheet metal embodying longitudinals comprising top and bottom longitudinally folded portions substantially channel-shaped 90 in cross-section, formed by folding the upper and lower edges of a blank of metal longitudinally, an intermediate web portion having diagonally disposed struts, interstrut openings and connecting rim strips, 95 the metal of each of such struts being embossed at its apex portion to one side of a plane passing through the said connecting rim strips and having the free flanges of such struts bent to the opposite side of such 100 a plane.

4. A rib for aerofoils comprising a single strip of sheet metal embodying longitudinals comprising top and bottom longitudinally-folded portions substantially channel-shaped in cross-section, formed by folding the upper and lower edges of a blank of metal longitudinally, an intermediate web portion having diagonally disposed struts, interstrut openings and connecting rim 105 strips, the metal of each of such struts being embossed at its apex portion to one side of a plane passing through the said connecting rim strips and having the free flanges of such struts bent to the opposite side of 110 such a plane, said embossing of the apex and bending of the flanges being to a substantially equal extent on opposite sides of said plane so that said plane will symmetrically cut opposite sides of the triangular 115 struts.

5. An aerofoil frame embodying a suitably disposed metallic marginal flange and a series of ribs secured thereto at opposite ends each comprising a single strip of sheet metal having longitudinals formed from top and bottom longitudinally folded portions substantially channel-shaped in cross-section, formed by folding the upper and lower edges of a blank of metal longitudinally and an inter- 125 130

mediate web portion having diagonally disposed struts and interstrut openings, the metal of each of the struts being bent laterally from edge to edge into a shape substantially triangular in cross-section.

6. An aerofoil frame embodying a suitably disposed metallic marginal frame and a series of ribs secured thereto at opposite ends, each comprising a single strip of sheet metal having longitudinals formed from top and bottom longitudinally folded portions substantially channel-shaped in cross-section, formed by folding the upper and lower edges of a blank of metal longitudinally, an intermediate web portion having diagonally disposed struts, interstrut

openings and connecting rim strips, the metal of each of such struts being embossed at its apex portion to one side of a plane passing through the said connecting rim strips and having the free flanges of such struts bent to the opposite side of such a plane.

In witness whereof, we have signed our names to the foregoing specification in the presence of two subscribing witnesses.
